United States Patent Office

Des. 222,392
Patented Oct. 19, 1971

222,392

VALVE BAG PACKER

Murland L. Taylor, 2521 Washington,
Parsons, Kans. 67357

Filed May 14, 1970, Ser. No. 22,969

Term of patent 14 years

Int. Cl. D15—08
U.S. Cl. D55—1

FIG. 1 is a bottom, rear perspective view of the valve bag packer embodying my new design;

FIG. 2 is a side elevational view thereof;

FIG. 3 is a bottom plan view thereof;

FIG. 4 is a front elevational view thereof; and

FIG. 5 is a rear elevational view thereof.

I claim:

The ornamental design for a valve bag packer, as shown.
